UNITED STATES PATENT OFFICE

JOHN BEITLER, OF BRENTWOOD, PENNSYLVANIA

SAFETY ATTACHMENT FOR WRINGERS

Application filed April 21, 1928. Serial No. 271,827.

This invention relates to safety means for clothes wringers, the general object of the invention being to provide means for conveying the clothes to and from the wringer, with means for enclosing the rollers of the wringer and adjacent parts of the conveying means so as to prevent the user from being injured by having his hands caught between the rollers or parts of the conveyor.

10 This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation with parts in section, showing the improved wringer attached to a tub.

Figure 2 is a plan view with parts in section.

Figure 3 is a section on line 3—3 of Figure 2.

Figure 4 is a section on line 4—4 of Figure 1.

30 Figure 5 is a section on line 5—5 of Figure 1.

Figure 6 is an enlarged vertical sectional view through the wringer and parts of the conveying means and the shields.

35 Figure 7 is a section on line 7—7 of Figure 6.

Figure 8 is a perspective view of one of the V-shaped members.

In these views, the numeral 1 indicates a 40 pair of side pieces attached at their inner ends to each side of the wringer, one at each end thereof, these side pieces extending outwardly and downwardly at an angle, as shown. The side pieces of each pair are connected together by a conveyor board 2 and upper and lower shafts 3 have their ends journaled in the side pieces, with the board extending between the shafts. A plurality of belts 4 pass over each pair of rollers 3, 50 with the upper reach of each belt passing

over the board. Each belt is provided with projections 5 for preventing the clothes slipping from the belts and board and insuring the clothes being carried up the conveyor from the tub to the rollers of the wringer, the 55 conveying means on the opposite side of the wringer conveying the clothes from the wringer into a tub or other receptacle which receives the clothes after they pass through the wringer. A cog 6 is attached to one end 60 of one of the pintles of the lower roll of the wringer and a pair of outer cogs 7 mesh with the cog 6. One of these cogs is arranged to one side of the wringer and the other at the opposite side thereof and each cog 7 meshes 65 with a cog 8 connected with each upper roller 3 so that the conveyor belts will be driven from the lower roll of the wringer. A V-shaped member 9 bridges the space between each upper roller 3 and the lower roll of the 70 wringer, each V-shaped member being yieldably supported from a part of the wringer by the brackets 10 provided with the spring arms 11 to which the ends of the V-shaped member are fastened, as clearly shown at 11' 75 in Figure 7. These parts are so constructed and arranged that the upper parts of the members 9 are yieldingly held against the lower roll of the wringer. Each V-shaped member is provided with notches 12 in its outer edges which form spaces for the passage of the projections on the conveyor belts.

A shield or guard 13 is hingedly connected with the upper part of the wringer at each side thereof, as shown at 14. The shields extend outwardly and downwardly at an angle and cover the rolls of the wringers and the upper or inner ends of the conveying means. Their outer ends are rounded, as shown at 15, so that clothes can readily pass under the 90 same by lifting the shields upwardly.

From the foregoing it will be seen that I have provided simple means for conveying clothes from a tub to a wringer and for conveying the clothes from the wringer to another receptacle, thus rendering it unnecessary for the user to place his fingers close to the rolls of the wringer in feeding clothes to the wringer or removing them from the wringer. The V-shaped members act to carry 100

the clothes from the conveyor to the rolls or from the rolls to the conveyor and by yieldingly supporting the V-shaped members, they are pressed against the lower roll so that the member which receives the clothes from the wringer will prevent the clothes from being wound around the lower roll thereof.

5 The shields or guards 13 prevent one from placing his hands too close to the rolls of the wringer or to the conveyor belts as they pass over the upper rollers.

It is thought from the foregoing description that the advantages and novel features of my invention will be readily apparent.

15 It is to be understood that I may make changes in the construction and in the combination and arrangement of the several parts, provided that such changes fall within the scope of the appended claims.

20 What I claim is:—

1. In combination with a wringer, means for conveying clothes to the wringer, means for conveying clothes from the wringer, means for driving both conveying means 25 from one of the rolls of the wringer, guards attached to the upper part of the wringer, one at each side thereof and extending outwardly and downwardly over the inner portions of the conveying means, members bridging the space between the upper ends of the conveying means and the lower roll of the wringer and means for yieldingly supporting the members with their upper portions against the lower roll of the wringer.

30 2. In combination with a wringer, means for conveying clothes to the wringer, means for conveying clothes from the wringer, means for driving both conveying means 35 from one of the rolls of the wringer, guards attached to the upper part of the wringer, one at each side thereof and extending outwardly and downwardly over the inner portions of the conveying means, members bridging the space between the upper ends

40 of the conveying means and the lower roll of the wringer and means for yieldably supporting the members with their upper portions against the lower roll of the wringer, each member being of V-shape in cross section with its pointed part resting upon the roll.

45 3. In combination with a wringer, a pair of side pieces attached to each side of the wringer, said pieces extending outwardly and downwardly at an angle, a conveyor board connecting the side pieces together, upper and lower rollers journaled in each pair of side pieces, conveyor belts carried by each pair of rollers, the upper reaches of the belts passing 50 over the board, projections on the belts, a cog attached to one end of the lower roll of the wringer, idle cogs meshing therewith, cogs on the upper rollers of the conveying means meshing with the idle cogs, bridging 55 members placed between the upper rollers of

the conveying means and the lower roll of the wringer, means for yieldingly supporting the bridging members and guards hingedly connected with the upper part of the wringer, one at each side thereof and extending downwardly and outwardly for covering the rolls of the wringer and the inner portions of the conveying means.

60 In testimony whereof I affix my signature.
